Primary Examiner — R. Johnson(74) *Attorney, Agent, or Firm* — Boudwin Intellectual Property; Daniel Boudwin(57) **CLAIM**

The ornamental design for a hybrid bass, as shown and described.

DESCRIPTION

FIG. 1 is a perspective view of the hybrid bass.

FIG. 2 is a front elevation view of the hybrid bass.

FIG. 3 is a rear elevation view of the hybrid bass.

FIG. 4 is a left side elevation view of the hybrid bass.

FIG. 5 is a right side elevation view of the hybrid bass.

FIG. 6 is a bottom plan view of the hybrid bass; and,

FIG. 7 is a top plan view of the hybrid bass.

The shade lines in the Figures show contour and not surface ornamentation.
